UNITED STATES PATENT OFFICE.

ALBERT JAMES WHITE, OF TORONTO, ONTARIO, CANADA.

PICTURE-FRAME VISE.

1,393,059.

Specification of Letters Patent. Patented Oct. 11, 1921.

Application filed January 28, 1920. Serial No. 354,706.

To all whom it may concern:

Be it known that I, ALBERT JAMES WHITE, a subject of the King of Great Britain, and resident of the city of Toronto, county of 5 York, Province of Ontario, in the Dominion of Canada, have invented certain new and useful Improvements in a Picture-Frame Vise, as described in the following specification, and illustrated in the accompanying 10 drawings, that form part of the same.

The principal objects of this invention are to facilitate the work of making picture frames and greatly reducing the cost of production, enabling a workman to accomplish 15 more work and to do it in a more effective manner and to devise a form of vise which is readily adaptable for handling various sizes of work and which will enable the operator to work without fatigue. 20 The principal feature of the invention consists in the novel construction of the vise head whereby the sides of the frame to be joined are properly positioned and whereby said sides are held by a movable member 25 adapted to engage both of the sides simultaneously.

In the drawings,

Figure 1 is a front side perspective view of the device showing the manner of locating 30 a frame therein.

Fig. 2 is a back elevational view.

Fig. 3 is a transverse section on the line 2-2 of Fig. 2.

Fig. 4 is an enlarged elevational view of 35 the vise head and holding block.

In the manufacture of picture frames considerable time is lost in the workman holding the mitered ends together for nailing and much difficulty is experienced in holding 40 the ends true. Various devices have been used to assist in this work but the best results obtained have been, up to the present, unsatisfactory.

In the device herein shown, the vise head 45 1 is formed with a flat perpendicular face 2 and at the top is provided with projecting flanges 3 arranged at an angle of 135° with the sides, such flanges being therefore arranged in right angular relation to each 50 other. The flanges do not, however, meet at the top and the frame moldings when placed against the under sides of these flanges project through the opening 4 at the upper end of the flanges and they are

thus open and free of access to the workman. 55

In order to hold the frame molding in position in snug contact with the underside of the flanges 3, a squared block 5 is supported upon a pin 6 and the pin extends 60 through a vertical slot 7 in the head 1, consequently when the pin is moved upwardly in the head the block will be brought into contact with the under side of the molding. 65

In order to provide for slight inequalities in the thickness of the moldings, the hole 8 in the block is larger than the pin thus allowing the block to center itself against the underside of the frame as is 70 shown particularly in Fig. 4. The head is formed with a longitudinal slot 9 in the rear side and in this slot is arranged a slideable rod 10, in the upper end of which the pin 6 is secured. This rod is operated by means 75 of a foot lever 11 pivotally supported upon a lug 12 arranged upon the base 13.

It is preferable that the vise head be adjustable in height to suit the workman and in order to accomplish this result I have 80 shown the base 13 in the form of a longitudinally slotted casing into which the rectangular stem 14 of the head extends. This stem slides in the hollow base and is suitably gripped in any desirable position, the 85 gripping means being here shown as a cam lever 15 pivotally supported in the lugs 16 arranged at one side of the base.

The flat rod 10 is slidably held in a longitudinal groove 17 in the back of the base 90 and the operating lever 11 is formed with a slot 18 engaging the pin 19 in said rod.

A coil spring 20 is preferably secured to the pin 19 to draw the rod downwardly 95 when the pressure on the foot lever is released to withdraw the block 5 out of engagement with the frame being built. The rod 10 must of course be made adjustable to suit the change in the height of the vise head and it is divided in its length, having 100 a longitudinal slot 21 formed in the upper portion through which a bolt 22 with an adjustable nut extends.

In the use of this device, the operator slips the two mitered portions to be joined 105 underneath the flanges 3 and pressure of the foot brings the block 5 into engagement with the under side of same, clamping it tightly

in position when the brads may be driven to secure the members together. All four corners of the frame may be thus assembled in a very rapid manner leaving the operator with both hands free.

The device always insures a properly squared joint and holds the frame absolutely secure while the nailing operation is being carried out.

10. The flanges 3 may be made so that they may be adjusted to suit various sizes of moldings by being moved closer together or farther apart at the top of the vise.

What I claim as my invention is:—

15. 1. A picture frame vise, comprising, a head having a flat face and a pair of flanges projecting from said face and arranged in right angular relation one to the other and spaced apart, and a block adapted to be moved into engagement with the molding to hold it

against said flanges, said block being supported so as to automatically adjust itself laterally to any inequality of width of molding.

2. A picture frame vise, comprising, a 25 head having a flat face and projecting angularly disposed flanges spaced apart, a pin slidably arranged in said head, and a rectangular block loosely mounted on said pin and adapted to hold the frame molding 30 against said flanges.

3. A picture frame vise comprising, a head having a flat face and projecting angularly disposed flanges spaced apart, a sliding member supported in said head and 35 having a pin projecting therefrom, and a rectangular block having a hole therein of larger diameter than said pin, said pin extending into said hole.

ALBERT JAMES WHITE.
